RAIL ANCHOR AND TIE PLATE

Harry A. Cook, Winnebago, Nebr.

Application November 30, 1936, Serial No. 113,521

2 Claims. (Cl. 238—364)

The invention relates to tie plates and more especially to combined rail anchors and tie plates.

One of the numerous troubles confronting rail roads is the prevention of the running or creeping of the rails of a track which causes too much expansion in some places and joints becoming too tight in other places, even becoming so tight that a rail will buckle in hot weather throwing the track out of alignment and thus making it dangerous for the passage of trains and frequently becoming tight enough on bridges to throw the framework out of line.

The primary object of the present invention is the provision of a plate of this character, wherein in the difficulties above expressed will be relieved in that the rails of a track will be successfully anchored against running in either direction or creeping and thereby eliminate kinks in the rails where the spikes are loose and thus assuring alignment irrespective of the size of the rails of the track.

Another object of the invention is the provision of a plate of this character, wherein the same will be firmly held in place and the rail anchored to avoid the creeping of the latter and also the shifting of the plate when upon the tie thereby giving greater life to the track and avoiding liability of the spreading of the rails and accidents incident thereto.

A further object of the invention is the provision of a plate of this character, which is simple in construction, thoroughly reliable and effective in its operation, durable, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary top plan view of a track rail and cross tie showing the combined rail anchor and tie plate constructed in accordance with the invention applied.

Figure 2 is a sectional view on the line 2—2 of Figure 1 looking in the direction of the arrows.

Figure 3 is a perspective view of the tie plate.

Figure 4 is a perspective view of one of the wedge keys for use with the tie plate.

Similar reference characters indicate corresponding parts throughout the several views in the drawing.

Referring to the drawing in detail, A designates

generally a portion of a track rail and B a portion of a tie, these being conventional and as usual the said rail is made fast to the tie by spikes 10 which in this instance are in association with a combined anchor and tie plate constituting the present invention and hereinafter fully described.

The plate constituting the present invention comprises a body section 11 having a flat bottom face 12 while intermediate the opposite ends of this plate at the top thereof is a rail base bearing 13 while upstanding from this body section at opposite sides of the bearing 13 rise shoulders 14 and 15, respectively.

Formed between the bearing 13 and the shoulder 15 is a channel-like keyway 16 which has its side walls 17 parallel with each other and uniformly spaced with relation to one another throughout the extent thereof. This keyway opens through opposite edges of the body 11 while provided in the said body and intersecting the shoulder 14 and the keyway 16 are spike holes 18 and 19, respectively, for accommodating the spikes 10 in fastening the plate body 11 superimposed upon the tie B. These spikes when driven through the holes 18 and 19 into the tie B engage with the base 20 of the rail A for the fastening of said rail in place and attached to the tie B, the base 20 of the rail being seated upon the bearing 13 of the plate body 11 as is clearly shown in Figure 2 of the drawing.

Insertable in the keyway 16 through opposite ends thereof are reversely arranged wedge shaped keys 21, these having outer driving heads 22 and each is formed with a reduced ledge or rib 23 at one longer side edge thereof to underlie the base 20 of the rail A so that this base will have contact with the key at the shouldered side 24 thereof when driven into the way 16 thus making secure the rail on the plate body 11. This rail at the edge opposite to that engaged by the keys 21 will abut the shoulder 14, these keys 21 become wedged in the keyway 16 when driven thereto by wedging action against the shoulder 15 and the base 20 of the rail next thereto. The ledge 23 of the keys 21 prevents the working upwardly of the said keys out of the keyway 16 in the use thereof.

Each key 21 has formed therein a notch 25 opening through the other longer edge of the key opposite the ledge 23 and this notch accommodates a spike 10 passed through the hole or opening 19 intersecting the keyway 16 and thus such key will be held secure and fast by the said spike.

The plate body 11 with the use of the keys 21

will anchor the rail A and the manner of attachment of the plate body 11 to the tie B avoids any possible creeping of the said rail and the kinking of the rail with the result that the said rails will 5 be out of alignment or spread from each other. By the use of the two keys 21 with the plate body 11 the rail can not creep in either direction longitudinally of the trackage.

Each key 21 from the opening 25 to the smaller 10 end thereof may be of a thickness corresponding to the thickness of the ledge 23 whereas the said key at the other end portion or at the opposite side of the opening 25 may be materially thickened with respect to the ledge 23.

15 What is claimed is:

1. A combined anchor and tie plate comprising a body having an inset rail bearing in its top face, said body at one side of the longitudinal center line of said bearing having a longitudinally extending groove provided with vertical side walls parallel with each other and to the longitudinal center line of said bearing, the outermost side wall of the groove being extended upwardly for effecting a shoulder, spike-like wedging keys inserted reversely to each other in opposite ends of the groove for engaging a rail base and the edge of the outermost side wall of the groove, and spikes passed through the keys and plate body 25

next to the inner ends of said keys and having heads overhanging the rail base for the fastening thereof upon the bearing, said keys and plate body having openings for said spikes adapted to register when the keys are in their driven positions. 5

2. A combined anchor and tie plate comprising a body having an inset rail bearing in its top face, said body at one side of the longitudinal center line of said bearing having a longitudinally extending groove provided with vertical side walls parallel with each other and to the longitudinal center line of said bearing, the outermost side wall of the groove being extended upwardly for effecting a shoulder, spike-like wedging keys inserted reversely to each other in opposite ends of the groove for engaging a rail base and the edge of the outermost side wall of the groove, spikes passed through the keys and plate body 10 next to the inner ends of said keys and having heads overhanging the rail base for the fastening thereof upon the bearing, said keys and plate body having openings for said spikes adapted to register when the keys are in their driven positions, and shallow flanges formed at the inner 15 sides of the wedging keys for underlying the rail base. 20

HARRY A. COOK.
